SAFETY RAZOR WITH INTEGRAL FOLDED BLADE

Anestis Foltis, Jackson Heights, N. Y.

Substituted for application Serial No. 215,755,
June 25, 1938. This application May 21, 1946,
Serial No. 671,283

5 Claims. (CL. 30—47)

1

This application is a substitute application for my application, Serial No. 215,755, filed June 25, 1938, now abandoned.

This invention relates to improvements in safety razors.

An important object of the invention is to provide an inexpensive safety razor having an integral razor blade of small size whereby the entire razor must be disposed of after the blade becomes too dull for shaving purposes.

A further feature of the invention is a safety razor wherein the blade and its holder have the form of a single unit which is simple and inexpensive in construction to enable its user to economically dispose of the entire unit after a limited number of shaves, thus eliminating the need of removing a used blade from its holder and replacing the same.

Another object of the invention is the provision of a safety razor unit in which the razor blade and holder is constructed from a single blank of flexible metal.

An additional feature of the invention is the provision of a razor blade holder in which the handle thereof is constructed of a pair of elements included in the blank and bent into position when the razor is needed for use.

The construction and advantages thereof will be apparent as the following specification is read in conjunction with the accompanying drawings, in which:

Figure 1 is a plan view of a blank for a razor presenting one form of the invention.

Figure 2 is a vertical transverse sectional view through a razor constructed from the blank shown in Figure 1, the section being taken through the middle of the construction shown in Figure 1 but with all parts in folded position.

Figure 3 is a plan view of a blank of a somewhat modified form.

Figure 4 is a top plan view of a razor constructed from a blank such as that shown in Figure 3.

Figure 5 is an enlarged vertical longitudinal sectional view on the line 5—5 of Figure 4.

Figure 6 is a plan view of a blank of a still further modified form.

Figure 7 is a top plan view of a razor constructed from the blank shown in Figure 6.

Figure 7A is a cross-section taken vertically through the middle of Figure 7.

In Figures 1 and 2, a single edge blade razor is constructed from a single blank of bendable metal L which includes a body portion 152 from which arms 153 extend, the said arms being

2

foldable on the fold lines 154, and extending beyond the arms 153 and foldable relative thereto on the lines 155 are finger grip elements 156. Extending from one side of the body 152 is a guard plate 157 which is formed with a row of spaced slots 158, the guard plate being folded over along the row of slots on the dot and dash lines 159. Integral with the guard plate 157 and foldable relative thereto on the line 159 is a single edge blade 160. Extending from the opposite side of the body 152 is a clamping plate 161 foldable over the body on the fold line 162. In folding the blank L, the same is first folded on the line 159 to cause a portion of the guard plate 157 to overlie the body 152 and to form the spaced guard fingers for the blade 160, after which the blade 160 is folded along the line 159 so as to be disposed adjacent the guard edge formed by the slots 158. The clamping plate 161 is folded over the blade 160 and the arms 153 folded under the body 152 with the finger elements 156 bent on the lines 155 to extend at right angle to the arms 153. The section 152, the plates 161 and 157, and the blade 160 constitute a wide intermediate portion of the strip and all the elements 161, 157 and 160 are bent along lines running lengthwise of the strip.

In the form shown in Figures 3 to 5 inclusive, a razor unit provided with a single edge blade is formed from a single blank of bendable metal M which is cut to provide a pair of guard plate sections 163 and 164 foldable one upon the other on the dot and dash lines 165. A row of spaced slots 166 extends along the line of fold 165 to provide guard fingers when the sections are folded one upon the other.

The guard sections 163 and 164 are provided with slots 167 and 168 respectively which register when the sections are folded on the line 165. Integral with the section 163 along the fold line 169 is a single edge blade 170 having an elongated slot 171 therein adapted to register with the slots 167 and 168 when the blank is folded into razor forming position. Extending from opposite ends of the section 163 and foldable on the lines 172, are clamping plate sections 173, the terminal ends of which are provided with flanges 174 foldable on lines 175. Integral with the guard plate section 164 is a handle or finger grip member 176 which is bendable on the fold line 177. In this form, the blade 170 is foldable over the guard plate section 163 after which the guard plate section 164 is foldable under the plate section 163, thus forming fingers out of the row of slots 166. The handle 176 is bent at

right angle to the folded guard plate section 164 and the clamping plate sections 173 are folded over the blade 170 with the flanges 174 bent to pass through the registering slots 171, 167, and 168, after which the terminal ends of the flanges are bent outwardly and underlie the guard plate section 163 as best illustrated in Figure 5.

In Figures 6, 7 and 7A, a single razor blade unit is formed from a single blank of bendable metal N which includes a guard plate 178 which is formed with a U-shaped slot 179, one edge of which is formed with spaced guard fingers 180. The material between the slot 179 and the outer edge of the blank constitutes a clamping or bridge rail 181 when the blank is folded into razor forming position. Extending integrally from opposite ends of the guard plate 178 and foldable on the fold lines 182, are arms 183, integral also with rail 181, and extending beyond the arms 183 and foldable on the lines 184 are finger grip elements 185. Integral with one edge of the guard plate 178, and foldable thereover on the fold line 186, is a single edge blade 187. In folding the blank N into razor forming position, the blade 187 is folded over the guard plate 178, after which the bridge rail 181 is folded upwardly over the blade 187 to overlie the same as illustrated in Figure 7, after which arms 183 are bent under the guard plate on the fold lines 182 to lie flat thereagainst, after which the finger grip elements 185 are bent to their handle forming position. In this form, it will be seen that the clamping rail 181 tends to clamp the blade in position against the guard plate 178.

While the razor unit may be constructed of steel, in instances where the blade is formed separate and joined to the blade holder, the holder may be constructed of sheet aluminum. Also, where the blade is integral with the holder, the entire unit is constructed of steel but only the cutting blade is heat treated to harden it.

While I have shown and described what I consider to be the preferred embodiment of my invention, I wish it to be understood that such modifications thereof may be resorted to as come within the scope of the appended claims.

Having thus described the invention, what I claim as new and desire to secure by Letters Patent of the United States, is:

1. A safety razor comprising a single elongated strip of bendable metal having a wide intermediate portion folded upon itself lengthwise of the strip to provide a pair of superposed inner and outer clamping plates, a razor blade interposed between said plates, the inner plate having guard teeth, and abutting handle members

formed at the ends of the strip overlying said inner clamping plate and extending outwardly from the inner plate midway thereof, the blade being integral with the one of said plates and united at one longitudinal edge thereof to said plate.

2. A safety razor comprising a single strip of bendable metal cut and folded to provide a relatively wide guard plate, a folded blade overlying said guard plate and integral with one of the longitudinal side edges thereof, means folded over said blade united to a longitudinal edge of the strip and securing the same against said guard plate, and a handle extending from said strip.

3. A safety razor comprising a single elongated strip of bendable metal cut and folded intermediate its ends to provide a relatively wide guard plate, a folded blade overlying said guard plate, the blade being integral with said plate and united thereto along one longitudinal edge, means carried by the strip for holding said blade against said guard plate, and a two part handle formed at the free terminal ends of said strip overlying said means and extending outwardly at right angle from said guard plate.

4. In a safety razor a strip having a clamping plate and a blade at opposite sides of the strip, said blade being folded lengthwise of the strip and said clamping plate also folded lengthwise of the strip and against the blade, the strip having arms adjacent the ends of the blade and plate, said arms carrying finger grip elements, said arms being folded against the plate and said elements extending outward of said plate.

5. A safety razor comprising a strip of flexible metal having an intermediate portion folded upon itself lengthwise of the strip to provide inner and outer clamping plates and a razor blade between said plates, the strip having means providing a handle for holding said razor, the blade being integral with one of said plates and united thereto along one longitudinal edge.

ANESTIS FOLTIS.
